CLAIM

The ornamental design for a baby chair, as shown and described.

DESCRIPTION

FIG. 1 is a first front and right side perspective view of a baby chair, showing my new design;

FIG. 2 is a second front and right side perspective view thereof;

FIG. 3 is a rear right side perspective view thereof;

FIG. 4 is a top view thereof;

FIG. 5 is a bottom view thereof;

FIG. 6 is a front view thereof;

FIG. 7 is a rear view thereof;

FIG. 8 is a right side perspective view thereof; and,

FIG. 9 is a left side perspective view thereof.

The broken lines in the drawings are shown for illustrative purposes only and form no part of the claimed design.
